UNITED STATES PATENT OFFICE

HOWARD WATERS DOUGHTY, OF AMHERST, MASSACHUSETTS

FIRE EXTINGUISHER

Application filed December 31, 1929. Serial No. 417,693.

This invention relates to fire extinguishers and is adapted for extinguishers of the portable type such as are carried to the fire and brought into operation by inversion or other 5 manual manner, or to extinguishers of the automatic type which are brought into operation automatically when the temperature in the vicinity of the extinguisher reaches a predetermined degree and/or when the pressure 10 within the extinguisher surpasses a predetermined maximum.

The invention further relates to extinguishers of the type in which the fire is "smothered" by spraying thereover a gas 15 or vapor of a substance which is non-combustible and non-combustion supporting. Such substances are well known and several of them are now in use. I have found carbon tetrachloride and other chlorinated 20 hydrocarbons or mixtures thereof to be admirably suited for this purpose.

The expulsion of the fire extinguishing substances from the extinguisher may be caused by pressure exerted by gas generated 25 within the extinguisher for that purpose by bringing together two reactive substances, one, or both, of which may be in liquid form, or the initial expulsion or discharge of the extinguishing substance may be caused by 30 pressure derived by other means and the subsequent expulsion of the substance caused by generated gas.

In fire extinguishers of the type in which the expulsion or discharge of the fire extinguishing substance is caused by a gas which is generated for that purpose it has been common to maintain in separate containers within the extinguisher an acid and a salt which will react therewith to liberate a gas. 35 Sulfuric acid and sodium bicarbonate are generally used, and the two are brought together with the resulting generation of carbon dioxide gas by inverting the extinguisher. The present invention differentiates 40 from such fire extinguishers essentially in the manner in which the reactive substances, which may be any suitable solid and solution, or two solutions which on contact produce 45 gas with sufficient rapidity, are maintained 50 within the extinguisher and in the manner

in which they are caused to be brought together for the generation of the expelling gas. Another important feature of the invention is the provision of an extinguisher in which all possibility of corrosion of the 55 container is eliminated.

In carrying out the present invention I use carbon tetrachloride or other fire extinguishing substance which is not miscible with water to any considerable extent and which 60 has a specific gravity greater than the solution or solutions which are used to generate the expelling gas. The reactive substances are caused to float on the fire extinguishing substance and are maintained out of contact 65 with each other until such time as it is desirable to cause the operation of the extinguisher. The separation of the reactive substances is preferably maintained by partitions which extend below the surface of the 70 fire extinguishing substance on which the reactive substances float. The reactive substances may be brought into contact to cause the generation of an expelling gas in various ways. For example, if the extinguisher is a 75 portable one, it may be inverted, as is now done with such extinguishers. If the extinguisher is of the automatic type the separating partition may be supported by a fusible connection which, at a predetermined 80 temperature permits the partition to drop, or, a frangible diaphragm may be provided which will be disrupted when the temperature 85 of the surrounding atmosphere exceeds a predetermined degree and the pressure within the extinguisher surpasses a predetermined amount. In the latter case the initial discharge of the fire extinguishing substance may be effected entirely by the vapor pressure of the extinguishing fluid and the subsequent 90 expulsion or discharge by the pressure of generated gas.

The invention will be further described in connection with the accompanying drawings but it is to be understood that this more detailed disclosure and description is intended 95 as an exemplification of the invention and that the same is not limited thereto. In the drawings:

Fig. 1 is a vertical sectional view of a fire

extinguisher embodying my invention, and Figs. 2 and 3 are views of modifications.

Referring now to the invention as illustrated in Fig. 1, the numeral 1 indicates a container for a fire extinguishing fluid 2, which, for reasons hereinafter pointed out, should not be miscible with water to any considerable extent and should preferably have a specific gravity somewhat greater than that of water. Carbon tetrachloride and other chlorinated hydrocarbons or mixtures thereof have been found to very satisfactorily fulfil these conditions.

The top 3 of the container 2 is provided with a relatively large opening 4 which is closed against the escape of vapors from within the container by a threaded closure 5. The closure 5 has formed integrally therewith an upstanding neck 6, the upper end of which terminates in a threaded flange 7 to receive the nozzle 8. The closure 5 and the integrally formed neck 6 are provided with a central opening 9 into which the upper end of a discharge tube 10 extends. The lower end of the tube 10, as is clearly shown in the drawings, extends down to a point adjacent the bottom of the container 1.

The nozzle 8 has an opening 11 registering with the opening 9. The opening 11 is threaded at 16 and is filled with a plug 12 which is fusible at the desired temperature. The filling of fusible material closes the opening in the nozzle and the lower end thereof rests on a diaphragm of frangible material 13 disposed between washers 14 and 15. The fusible material thereby acts as a reinforcement for the diaphragm 13 and prevents its rupture until the desired temperature has been reached. The particular construction of the neck 6, together with the frangible diaphragm 13 and fusible reinforcing material, is disclosed in my Patent No. 1,736,256, granted Nov. 19, 1929 and forms no part of the present invention, and any other type of release may be used if desired.

In order that the expulsion discharge of the fire extinguishing fluid 2 shall not be dependent merely upon the vapor pressure of the extinguishing fluid, reactive, gas generating substances 16' and 17 are disposed within the container. These substances may be a non-volatile solid, for example, sodium carbonate and a solution, or two solutions, preferably in water, which on contact produce gas with sufficient rapidity. Sulphuric acid and a solution of potassium carbonate are examples of two liquid substances which may be used. The potassium carbonate is used in preference to the cheaper sodium carbonate or sodium bicarbonate because it is more soluble and more of it can be used in a given volume of solution, thus saving space for the fire extinguishing fluid. The use of these gas generating substances together with carbon tetrachloride as the extinguishing fluid

provides a fire extinguisher which has a very low freezing point and one which delivers a completely neutralized liquid.

The sulphuric acid and potassium carbonate are both non-reactive with carbon tetrachloride and when the sulphuric acid is suitably diluted with water both of them will have a specific gravity which is less than the carbon tetrachloride and will float directly thereon.

To maintain the sulphuric acid out of contact with the potassium carbonate until such time as it is desired to have the extinguisher set in operation they are separated by a partition 18. The partition 18 may be composed of any material which does not react with the acid or carbonate solution. Lead, fiber and bakelite are examples of such materials.

The partition 18 has its lower end extending a slight distance below the level of the carbon tetrachloride solution so that swashing of the contents of the extinguisher will not cause the acid and carbonate to be brought into contact with each other. In the drawings the partition has been shown as a cylinder concentric with the discharge tube 10 but it is to be understood that this partition may take any form as long as it maintains the reactive substances out of contact with each other.

The upper end of the partition 18 is suitably supported by a fusible connection 19, which comprises a supporting ring 20 of fusible material resting upon inturned ends 21 of lugs 22 depending from the under side of the closure 5. The partition 18 may, if desired, be supported by the shell of the container or by the discharge tube 10.

The container 1 is provided with lugs 23 to which the lower ends of a bail 24 are secured. This bail provides for mounting the extinguisher at the proper distance from the ceiling.

The extinguisher as above constructed is charged by pouring carbon tetrachloride in until the container is about three fourths full. Then fifty percent sulphuric acid, saturated aluminum sulphate or other substitute is added on one side of the partition 18 and potassium carbonate solution on the other side of the partition 18. The amounts of these solutions are determined by the capacity of the container but will roughly comprise about one eighth the total volume. These solutions will, as stated above, float on top of the carbon tetrachloride. The extinguisher thus charged is hung up to await a fire. When a fire occurs the heat of the surrounding atmosphere melts the fusible ring 20 which holds the partition 18 in place and permits the partition to drop. The dropping of the partition allows the acid substance and carbonate to contact and react with the resulting generation of carbon dioxide gas. The extinguisher is now ready

to operate as soon as the dual temperature and pressure control means 12 and 13 will permit the discharge of the carbon tetrachloride.

5 In Fig. 2 I have shown the invention applied to a fire extinguisher of the portable type. In this figure the container 31 is adapted to be maintained in upright position until its use becomes necessary. The container 31 19 is provided with a discharge opening 32 near the upper end thereof which communicates with a hose 33, equipped with a spray nozzle 34, by means of which the operator may direct the discharge of the extinguishing fluid 15 35 onto the fire.

The top of the container 31 is provided with an upwardly or outwardly extending neck 36, the upper edge of which is provided with screw threads 37 which cooperate 20 with similar threads on the interior of a flanged cover 38.

Aligning with the outwardly extending neck 36 is an inwardly extending flange 39 the inner end of which is turned at right 25 angles to form a supporting ledge 40 for a partition 41 which, like the partitions 18 and 18' in the forms heretofore described maintains the reactive substances 42 and 43 out 30 of contact until such time as it is desired to bring the extinguisher into operation. The partition 41 has upwardly extending fingers 44 provided with outwardly turned ends 45 which engage the supporting ledge 40 to hold 35 the partition in place. The partition 41 extends below the level of the fire extinguishing fluid 46 which, as in the forms of the invention previously described, is preferably carbon tetrachloride or other chlorinated hydrocarbons or mixtures thereof.

40 The partition 41 is shown as a cylinder having an opening at both ends. To prevent splashing when in normal position the upper end of the cylinder may be provided with a loose fitting cover 47 which will drop off 45 when the extinguisher is brought into operation.

The extinguisher shown in Fig. 2 is charged in the same manner as the extinguishers heretofore described. When it is desired to bring 50 the extinguisher into operation it is only necessary to invert it. The inversion of the extinguisher causes the lighter acid and carbonate to rise beyond the separating partition to the surface of the carbon tetrachloride where 55 they come in contact with each other with the resultant generation of carbon dioxide which is the impelling force which causes the discharge or expulsion of the carbon tetrachloride.

60 In Fig. 3 I have shown a modification of my invention in which all danger of corrosion due to the acid solution coming in contact with the inner surface of the container is avoided. This modification is shown in connection with an automatic type of extin-

guisher but it is likewise applicable to extinguishers of the portable type.

The construction and operation of the extinguisher shown in Fig. 3 is similar to the construction and operation of the extinguisher shown in Fig. 1, but instead of a single partition such as is disclosed in that figure, two partitions 50 and 51 are shown. In this form of the invention the inner partition 50 maintains the acid and carbonate solutions separate, while the outer partition 51 maintains the substance between the partitions out of contact with the inner surface of the container 1^a. The partitions 50 and 51 are composed of such material as will resist the corrosive action of the acid and carbonate solutions and are supported by fusible connections 52 and 53, similar to the fusible connection 19 of Fig. 1.

When desired to prevent excessive swashing of the contents the fire extinguisher shown in the various figures may be provided with baffles or other antisplash means, which may be secured to the interior of the casing and/or to the partitions.

From the foregoing description it will be apparent that I have provided a fire extinguisher having means for effectively maintaining the reactive substances out of contact with each other until such time as it is desired to set the extinguisher in operation and that once set in operation the discharge of the fire extinguisher will continue irrespective of any subsequent cooling of the atmosphere immediately adjacent the extinguisher. The present invention also provides a fire extinguisher which is devoid of all moving parts and which is extremely simple in operation.

I claim:

1. A fire extinguisher comprising a container having a discharge opening, a fire extinguishing liquid in said container, gas-producing reactive substances floating on said fire extinguishing liquid, a partition for normally maintaining said reactive substances out of contact with each other, and fusible means for supporting said partition in normal position.

2. A fire extinguisher comprising a container having a discharge opening, a fire extinguishing liquid in said container, gas-producing reactive substances floating on said fire extinguishing liquid, and partitions for normally maintaining said reactive substances out of contact with each other and out of contact with the inner surface of the container.

3. A fire extinguisher comprising a container having a discharge opening, a fire extinguishing liquid in said container, gas-producing reactive substances floating on said fire extinguishing liquid, and partitions for normally maintaining said reactive substances out of contact with each other and out of contact with the inner surfaces of the container,

and fusible means for supporting said partitions in normal position.

4. A fire extinguisher comprising a container having a discharge opening, a fire extinguishing liquid in said container, gas-producing reactive substances floating on said fire extinguishing liquid, a partition for normally maintaining said reactive substances out of contact with each other, and fusible means within the container for supporting said partition in normal position.

5. A fire extinguisher comprising a container having a discharge opening, a fire extinguishing liquid in said container, gas-producing reactive substances floating on said fire extinguishing liquid, partitions for normally maintaining said reactive substances out of contact with each other and out of contact with the inner surface of the container, and fusible means within the container for supporting said partitions in normal position.

6. A fire extinguisher comprising a container having a discharge opening, a fire extinguishing liquid in said container, gas-producing reactive substances floating on said fire extinguishing liquid, and partitions extending below the surface of the extinguishing fluid and normally maintaining said reactive substances out of contact with each other and out of contact with the inner surface of the container.

7. A fire extinguisher comprising a container having a discharge opening, means subject to dual control of temperature and pressure for normally maintaining said opening closed, a discharge tube communicating with said discharge opening and extending to near the bottom of the container, a fire extinguishing liquid within said container and surrounding said discharge tube, gas-producing reactive substances floating on said fire extinguishing liquid, a partition for normally maintaining said reactive substances out of contact with each other, and fusible means for supporting said partition in normal position.

8. A fire extinguisher comprising a container having a discharge opening, means subject to dual control of temperature and pressure for normally maintaining said opening closed, a discharge tube communicating with said discharge opening and extending to near the bottom of the container, a fire extinguishing liquid within said container and surrounding said discharge tube, gas-producing reactive substances floating on said fire extinguishing liquid, and partitions for normally maintaining said reactive substances out of contact with each other and out of contact with the inner surface of the container.

9. A fire extinguisher comprising a container having a discharge opening, means subject to dual control of temperature and pressure for normally maintaining said opening

closed, a discharge tube communicating with said discharge opening and extending to near the bottom of the container, a fire extinguishing liquid within said container and surrounding said discharge tube, gas-producing reactive substances floating on said fire extinguishing liquid, partitions for normally maintaining said reactive substances out of contact with each other and out of contact with the inner surface of the container, and fusible means for supporting the said partitions in normal position.

10. A fire extinguisher comprising a container having a discharge opening, a fire extinguishing liquid in said container, gas producing reactive substances floating on said fire extinguishing liquid and a cylindrical partition having an opening at each end to the interior of the container for normally maintaining said reactive substances out of contact with each other.

In testimony whereof I affix my signature.
